O. H. SCHUH

HOISTING APPARATUS

Filed July 19, 1926

Inventor
O. H. Schuh,

By Clarence A. O'Brien
Attorney

UNITED STATES PATENT OFFICE.

OTTO H. SCHUH, OF DENVER, COLORADO.

HOISTING APPARATUS.

Application filed July 19, 1926. Serial No. 123,583.

My present invention pertains to hoisting apparatus, and contemplates the provision of a hoisting apparatus so characterized that it is adapted to be used in general to advantage 5 but is more especially adapted for the purpose of enabling steam fitters, plumbers and other operatives to place a radiator or other heavy object at or against a ceiling or at any intermediate point between a floor and ceiling.

Other objects and practical advantages of the invention will be fully understood from the following description and claims when the same are read in connection with the 15 drawings, accompanying and forming part of this specification, in which:

Figure 1 is a broken view, partly in side elevation and partly in section, illustrating the apparatus constituting the preferred 20 embodiment of my invention.

Figure 2 is a horizontal section taken in the plane indicated by the line 2—2 of Figure 1, looking downwardly.

Figure 3 is a horizontal section taken in 25 the plane indicated by the line 3—3 of Figure 1, looking downwardly.

Figure 4 is a fragmentary diametrical section 30 illustrative of the manner in which the tubular post of the improvement may be increased in length.

Figure 5 illustrates the manner in which an 35 electric motor may be used in the apparatus for the actuation of the drum and the holding of same against casual movement.

Similar numerals of reference designate 40 corresponding parts in all of the views of the drawings.

Among other elements the embodiment 45 illustrated comprises a base 1 in which is stepped and journaled the lower end of an upright threaded member 2, the said threaded member 2 being superposed on a nut 2^x equipped with lateral handles 3 whereby it may be powerfully turned about its axis on the member 2.

Supported by the member or nut 2^x on the 50 screw member 2 is a rectilinearly movable tubular post 4, the lower portion of which is interiorly smooth so as to be capable of moving rectilinearly on the upper portion of screw 2.

Carried in brackets 5 on the post 4 is a 55 drum 6 which is shown in Figures 1 and 3 as equipped with a ratchet disk 7 for cooperation with a dog 8, designed to prevent casual retrograde rotation of the drum 6. As

shown in said figures the said drum 6 is also equipped with a crank handle 9 for manual turning of the drum. In this connection, however, I would have it understood that 60 when deemed expedient the drum 6 may be equipped with a worm gear meshed with a worm designed to be turned by any appropriate motor, such as the electric motor 6^x of Figure 5, and when the cooperating worm 65 gear and worm are employed it will be understood that with the worm idle casual retrograde rotation of the drum 6 will be strongly prevented.

The post 4 is provided at its upper end with a plate 10, and it will be readily understood that by manipulation of the nut 2^x the plate 10 may be held under pressure against a ceiling or may be held under tension against guy cables, not illustrated, with a view to maintaining the post 4 in upright position. Supported in a diametrical slot 11 in post 4 is a sheave 12, vertically disposed, and serving for the support and play of a cable 13, the said cable being associated with and adapted to be taken up on the drum 6. At its end remote from the drum 6 the said cable 13 is connected to a vertically movable member 14 provided with a sleeve 15 that receives and is movable vertically on the post 4, and also provided with an appropriate platform portion 16 which may be of any desired shape and area within the purview of my invention. Said sleeve 15 is slotted and provided with an offset portion 15^x, Figures 1 and 2 for the play 80 of sheave 12. Manifestly by turning of the drum 6 in the proper direction the member 14 may be raised or lowered on the post 4, and through the medium of the means before alluded to the member 14 may be adjustably 85 positioned at various heights.

In the embodiment illustrated a horizontally swingable crane arm 16^x is pivoted at 17 to the member 14, the said crane arm 16^x being preferably equipped with a cable 18 that carries a hook or other appropriate appurtenance 19, and the said crane arm 16^x is adapted to be swung horizontally in opposite directions to enable an operative to pick objects spaced from the post 4 and place such objects or object at various points about the post 4.

By comparison of Figures 1 and 4 it will be understood that in lieu of the post 4 equipped with the plate 10 at its upper end, a plain post 4^a such as employed in Figure 4 may form the lower section of the post, and

the said section may have fixed in its upper portion an upwardly extending member 4^b, and an upper section 4^c may be arranged telescopically upon the section 4^b and disposed and supported at 4^d on the section 4^c; it being understood in this connection that the plate 10 will be carried by the section 4^c. It will also be understood that the embodiment just alluded to and illustrated in Figure 4 is to permit of the post of the apparatus being increased in length when occasion demands.

It will be apparent from the foregoing that my novel apparatus is adapted to be operated with facility and with the expenditure of but little effort, and that the apparatus is calculated to lend itself to the ready placing of radiators and other heavy objects at or against the ceiling of an apartment or at any intermediate point between the floor and ceiling.

I have explicitly described the preferred embodiment of my invention in order to impart an exact understanding of the said embodiment in all of its details. I do not desire, however, to be understood as limiting myself to the precise construction disclosed, my invention being defined by my appended claims within the scope of which modifications may be made without departure from my invention.

Having described my invention, what I claim and desire to secure by Letters Patent, is:—

1. In a hoisting apparatus and in combina-

tion, an upright post having a diametrical slot in its upper portion, a member movable vertically on the post, and having a sleeve receiving the post, said sleeve being provided with a slot and with an offset portion opposite the slot, a sheave mounted in the slotted portion of the post and disposed in the post slot and the sleeve slot and adapted to move in the offset portion of the sleeve, a cable trained over the sheave and connected to the vertically movable member and crane means carried by and extending laterally from said sleeve of the vertically movable member.

2. In a hoisting apparatus and in combination, an upright post having a diametrical slot in its upper portion, a member movable vertically on the post, and having a sleeve receiving the post, said sleeve being provided with a slot and with an offset portion opposite the slot, a sheave mounted in the slotted portion of the post and disposed in the post slot and the sleeve slot and adapted to move in the offset portion of the sleeve, a cable trained over the sheave and connected to the vertically movable member, and crane means carried by and extending laterally from said sleeve of the vertically movable member; the said crane means comprising a platform portion fixed to and extending laterally from the said sleeve, and a horizontally swingable crane arm pivoted to the said platform portion.

In testimony whereof I affix my signature.

OTTO H. SCHUH.
